(Cl. D47—7)

Fig. 2.

FIGURE 2 is an enlarged elevational view of the fabric forming the body of the stocking constituting our new design; and

FIGURE 2 shows the design in its actual scale and the vertical heavy black line in the center of this figure represents the seam of the stocking.

The welt and foot portions of the stocking are of conventional construction.

We claim:

The ornamental design for a stocking, as shown and described.
